UNITED STATES PATENT OFFICE.

FRANCIS P. MCGOVERN, OF NEW YORK, N. Y.

DESIGN FOR A HOUSEHOLD ALTAR OR SHRINE.

SPECIFICATION forming part of Design No. 19,922, dated June 24, 1890.

Application filed April 21, 1890. Serial No. 348,916. Term of patent 7 years.

To all whom it may concern:

Be it known that I, FRANCIS P. MCGOVERN, of New York, in the county and State of New York, have invented and produced a new and original Design for a Household Altar or Shrine, of which the following is a specification, reference being had to the accompanying drawings, forming a part thereof.

Figure 1 is a front elevation of the altar or shrine; and Fig. 2 is a side elevation, deemed necessary to more fully illustrate the position of the main figure of the design.

My design consists in the representation of a stepped base figure A, above which is a mainly rectangular figure B, showing at its upper portion the inclined lines b, terminating in a smaller rectangular upward continuation b'. In the lower corners of the figure B are quadrantal figures g, on which are indicated figures with harps. At the sides of the figure B are pilaster-like figures e, surmounted by an arch-like figure f, extending

across the upper portion of the figure B. Within the apparent niche bounded on the sides by the pilasters e and above by the arch f are the vase representations e', on which appear bouquets of flowers, and around the niche are shown simulations of silken drapery. Centrally between the quadrantal figure g a veiled and draped figure C is shown resting upon a portion of a sphere. In front of the quadrantal figures g vases h are shown, also the lines of candelabra, and a taper-lamp between said candelabra, the vases, taper-lamp, and candelabra appearing to rest on parallel 30 lines of the stepped figure A.

I claim—

The design for a Household altar or shrine herein shown and described.

FRANCIS P. MCGOVERN.
